SPOON OR SIMILAR ARTICLE OF FLATWARE

Robert A. Eckersberg, Chicago, Ill., assignor to Ekco Products Company, Chicago, Ill., a corporation of Illinois

Filed June 30, 1960, Ser. No. 61,165

Term of patent 14 years

(Cl. D54—12)

FIG. 1 is a front elevational view of a spoon or similar article of flatware showing my new design.

FIG. 2 is a side elevational view thereof.

FIG. 3 is an enlarged transverse sectional view taken on line 3—3 of FIG. 1.

FIG. 4 is an enlarged transverse sectional view taken on line 4—4 of FIG. 1.

I claim:

The ornamental design for a spoon or similar article of flatware, as shown.
